[57] ABSTRACT

A contactless ignition system for internal combustion engines comprising: at least one charging circuit including a series combination of a capacitor charging coil for generating an output by the rotation of a permanent magnet, rectifying means for rectifying the generated output of the capacitor charging coil and a capacitor, with the flow of current being directed from the capacitor charging coil to the capacitor through said rectifying means; at least one discharging circuit including a series combination of said capacitor and a thyristor having a gate to cause said capacitor to discharge its stored charge upon conduction of said thyristor; at least one ignition coil having a primary winding and a secondary winding; and at least one transformer having at least one primary winding and secondary winding, respectively, with the primary winding electrically connected to said capacitor charging coil to thereby detect the generated output thereof, wherein the primary winding of said ignition coil is connected in series in said discharging circuit, wherein at least one spark plug is connected to the secondary winding of said ignition coil, and wherein the secondary winding of said transformer is electrically connected to the gate of said thyristor.

FIG. 47

CONTACTLESS IGNITION SYSTEM FOR INTERNAL COMBUSTION ENGINES

The present invention relates to a capacitor discharge ignition system of the type which eliminates the breaker points and in which a magneto generator driven by the internal combustion engine installed in a vehicle or the like is utilized as a charging source.

It is an object of the present invention to provide a contactless ignition system which is simple in construction and inexpensive and in which a thyristor for discharging the stored charge of a capacitor is controlled by a transformer which detects the generated output of a capacitor charging coil, whereby there is no need for any generator for generating ignition timing signals.

The above and other objects and advantages of the present invention will be readily apparent from the following detailed description of preferred embodiments of the invention taken in conjunction with the accompanying drawings, in which:

FIG. 1 is an electrical wiring diagram of a first embodiment of an ignition system according to the present invention;

FIG. 2 is a diagram showing the waveforms at various portions of the system of FIG. 1, useful for explaining the operation thereof;

FIGS. 3a and 3b are electrical wiring diagrams of a second embodiment of the system according to the present invention;

FIG. 4 is a diagram showing the waveforms at various portions of the circuit of FIG. 3, useful for explaining the operation thereof;

FIGS. 5a and 5b are perspective views of the stators used with the magneto generator of the system shown in FIG. 3;

FIGS. 6a and 6b, and FIGS. 7 to 11 are electrical wiring diagrams showing the 3a, 3b to eighth embodiments of the system according to the present invention;

FIG. 3c, FIGS. 6c to 6h, FIG. 7-1 and FIG. 8-1 are circuit diagrams showing examples of the electrical connection of a capacitor charging coil and a transformer according to the present invention;

FIG. 12 and FIG. 13 are diagrams showing the waveforms at various portions of the systems of FIGS. 10 and 11, useful for explaining the operation of the embodiments of FIGS. 10 and 11;

FIG. 14 is a plan view showing, in section, the principal part of the structure of the magneto generator employed in the embodiments shown in FIGS. 10 and 11;

FIGS. 15 to 17 are electrical wiring diagrams showing ninth to eleventh embodiments of the system according to the present invention;

FIG. 18, FIG. 19 and FIG. 20 are diagrams showing the waveforms at various parts of the systems of FIGS. 15 to 17, useful for explaining the operation of the embodiments shown in FIGS. 15 to 17;

FIGS. 21 to 27 are electrical wiring diagrams of twelfth to eighteenth embodiments of the system according to the present invention;

FIG. 28 is an output characteristic diagram of the capacitor charging coil employed in the embodiments shown in FIGS. 23 to 25;

FIG. 29 is a diagram showing the waveforms at various portions of the circuit of FIG. 26, useful for explaining the operation of the embodiment shown in FIG. 26;

FIGS. 30 to 32 are electrical wiring diagrams of nineteenth to twenty-first embodiments of the system according to the present invention;

FIG. 33 is a diagram showing the waveforms at various portions of the circuit of FIG. 30, useful for explaining the operation of the embodiment shown in FIG. 30;

FIG. 34 is an electrical wiring diagram of a twenty-second embodiment of the system according to the present invention;

FIG. 35 is a plan view showing, in section, the principal part of the structure of the magneto generator used in the embodiment shown in FIG. 34;

FIGS. 36a to 36f are electrical wiring diagrams showing further examples of the electrical connection of the capacitor charging coil and transformer according to the present invention;

FIGS. 37a and 37b are electrical wiring diagrams showing the 23a and 23b embodiments of the system according to the present invention;

FIG. 38 is a plan view showing, in section, the principal part of the structure of the magneto generator used in the embodiment shown in FIG. 37;

FIGS. 39 to 42 are electrical wiring diagrams of twenty-fourth to twenty-seventh embodiments of the system according to the present invention;

FIGS. 43 and 44 are schematic diagrams showing the construction of the transformers used in the embodiments shown in FIGS. 39 and 41, respectively;

FIG. 45 is a waveform diagram for explaining the operation of the embodiment shown in FIG. 39;

FIG. 46 is a plan view showing, in section, the principal part of the structure of the magneto generator used in the embodiments shown in FIGS. 39 to 42;

FIG. 47 is a diagram useful for explaining the ignition timing of a two-stroke cycle engine.

The present invention will now be explained with reference to the embodiments illustrated in the accompanying drawings. Referring first to FIG. 1 illustrating a first embodiment, designated at G is a magneto generator driven by an internal combustion engine and provided with a rotor having four poles, for example, to generate in a generating coil 1 (capacitor charging coil) an AC output having a frequency of two cycles per revolution. Numeral 2 designates a current transformer which is a kind of transformer having a primary winding 2a and a secondary winding 2b with the primary winding 2a being connected in series with the non-grounded side of the generating coil 1. Numeral 3 designates a diode constituting a rectifying means; 4 a thyristor constituting a semiconductor switching element having its control electrode connected to the ground through a parallel circuit comprising a protective diode 5 and the secondary winding 2b of the current transformer 2. Numeral 6 designates a capacitor having one end connected to the primary winding 2a of the current transformer 2 through the diode 3 and also connected to the ground by way of a parallel circuit comprising the anode and the cathode of the thyristor 4 and a resistor 7, and the other end is grounded through a parallel circuit comprising a diode 8 and a primary winding 9a of an ignition coil 9. A secondary winding 9b of the ignition coil 9 is connected to a spark plug 10.

With the arrangement described above, the operation of the first embodiment of the present invention will be explained. When the generator G rotates, an AC

voltage e is produced in the generating coil 1 as shown in FIG. 2(a), and this AC voltage e charges the capacitor 6 through the path comprising the primary winding 2a of the current transformer 2, diode 3, capacitor 6, diode 8 and the primary winding 9a of the ignition coil 9. The waveform of a charging current I_c flowing into the capacitor 6 is shown in FIG. 2(b). The polarity of the secondary winding 2b of the current transformer 2 is preselected so that a positive voltage is applied to the control electrode of the thyristor 4 when the charging current I_c of the capacitor 6 begins to decrease from its peak value. The waveform of the voltage V induced in the secondary winding 2b of the current transformer 2 is shown in FIG. 2(c). In this way, as will be seen from the waveform of the capacitor charging voltage E shown in FIG. 2(d), when the charging of the capacitor 6 is practically completed, the thyristor 4 is conducted by a voltage generated in the secondary winding 2b of the current transformer 2, so that the stored charge in the capacitor 6 is discharged through the thyristor 4 and the primary winding 9a of the ignition coil 9, inducing a high voltage in the secondary winding 9b of the ignition coil 9 and thereby supplying an ignition spark to the spark plug 10. The resistor 7 is a high-resistance discharging resistor provided to maintain the capacitor 6 in a completely discharged state when it is to be charged to provide an initial ignition spark. As shown by broken lines in FIG. 1, the resistor 7 may be connected in parallel with the capacitor 6, or alternatively it may be connected in parallel with the diode 3. The purpose of the diode 8 is to extend the arc duration time of ignition sparks.

FIGS. 3a and 3b illustrate a second embodiment of the present invention. In this embodiment, a half wave of an AC output from the generating coil 1 which is opposite in polarity to the charging half-wave is utilized to produce an output in the secondary winding 2b of the current transformer 2. The generating coil 1 is designed such that as the speed of the engine increases, the impedance of the generating coil 1 increases increasing the voltage drop in the coil and thus reducing the charging voltages for the capacitor 6. In this embodiment, the generating coil 1 comprises a low-speed capacitor charging winding 1a adapted to generate more output at low engine speeds and a high-speed capacitor charging winding 1b of a thicker wire diameter and smaller number of turns than the winding 1a to provide more output at higher engine speeds. The windings 1a and 1b are connected in series so that at low engine speeds, the capacitor 6 is charged mainly by means of the low-speed capacitor charging winding 1a through the high-speed capacitor charging winding 1b, while at high engine speeds the capacitor 6 is charged mainly by the high-speed capacitor charging winding 1b, but not through the low-speed capacitor charging winding 1a. The primary winding 2a of the current transformer 2 is connected in parallel with the low-speed capacitor charging winding 1a through a rectifying diode 12, and a rectifying diode 11 is connected in parallel with a series circuit comprising the low-speed capacitor charging winding 1a and the diode 3 constituting a rectifying means.

According to the second embodiment, the polarity of the secondary winding 2b of the current transformer 2 is selected so that when the capacitor 6 has been charged by positive output voltages of the capacitor charging windings 1a and 1b and the charging current

I_c for the capacitor 6 has decreased from its peak value completing the charging of the capacitor 6 and when negative voltages are produced in the windings 1a and 1b causing a current I_h of negative phase in the primary coil 2a of the current transformer 2, a positive voltage is applied to the control electrode of the thyristor 4. FIG. 4(a) shows the waveform of the AC voltage e in the windings 1a and 1b; FIG. 4(b) the waveform of the charging current I_c for the capacitor 6; FIG. 4(c) the waveform of the current I_h supplied to the primary winding 2a of the current transformer 2; FIG. 4(d) the waveform of the voltage V induced in the secondary winding 2b of the current transformer 2; and FIG. 4(e) the waveform of the charging voltage E for the capacitor 6.

In the second embodiment, the magneto generator G is of a four-plate type having a rotor carrying four poles which alternately have different polarities circumferentially, and the stator is constructed either as shown in FIG. 5a in which the low-speed capacitor charging winding 1a (generating winding) with a higher number of turns and the high-speed capacitor charging winding 1b (generating winding) with a smaller number of turns are wound on separate cores 13 and 14, respectively which are disposed longitudinally one upon another to be secured on a fixed plate 15, or as shown in FIG. 5b in which the cores 13 and 14 having the respective windings 1a and 1b wound thereon are axially disposed in juxtaposition on the fixed plate 15. Numerals 16 and 17 designate a current generating coil and core, respectively, serving as a power supply for an electrical load carried on the vehicle, such as a lamp.

In the embodiment shown in FIGS. 3a and 3b, the diode 11 also serves to prevent misoperation of the thyristor 4 under the high speed operating conditions. In other words, this will be clear, if the operation of the system without the diode 11 is considered. Namely, under the low speed operating conditions the impedance of the generating winding 1a is at a low value and hence the generated voltage of the generating winding 1b is also low. Thus, while, under the low speed operating conditions, a current that flows through the path connecting the generating coil winding 1b, diode 12, primary winding 2a of current transformer 2, diode 3, capacitor 6, parallel circuit consisting of diode 8 and primary winding 9a of ignition coil 9 and the ground in the case of FIG. 3a, or through the path connecting the generating coil winding 1b, capacitor 6, parallel circuit consisting of diode 8 and primary winding 9a of ignition coil 9, ground, diode 3, primary winding 2a of current transformer 2 and diode 12 in the case of FIG. 3b, is small and hence the secondary output of the current transformer 2 cannot conduct the thyristor 4, at high engine speeds the impedance of the generating winding 1a increases and an increased voltage is generated in the winding 1b causing a large current flow through the path and thereby inducing an output in the secondary winding 2b of the current transformer 2 which is sufficient to cause the thyristor 4 to conduct erroneously. The diode 11 serves to prevent such a large current flow through the path under the high speed operating conditions.

In FIG. 6a, there is illustrated an embodiment numbered 3a of the present invention. This embodiment differs from the second embodiment in that the generating coil 1 wound on a single core is divided by means of a center tap 1c into a low-speed capacitor charging

coil portion 1a having a large number of turns and a high-speed capacitor charging coil portion 1b having a small number of turns. The primary winding 2a of the current transformer 2 is connected in parallel with the high-speed capacitor charging coil portion 1b and a rectifying diode 18 is connected in parallel with the low-speed capacitor charging coil portion 1a.

With the arrangement described above, the third embodiment shown in FIG. 6a operates as follows. Assuming now that an AC voltage is generated in the generating coil 1 (capacitor charging coil) so that a positive-going half wave voltage with respect to the ground is generated, the capacitor 6 is charged in a polarity shown through the circuit comprising the capacitor charging coil portions 1a and 1b, diode 3, capacitor 6, parallel circuit consisting of diode 8 and primary winding 9a of ignition coil 9 and ground.

As the magneto generator G rotates further so that the polarity of the generated voltage in the generating coil 1 (capacitor charging coil) is reversed on the following half cycle, the generated voltage in the low-speed capacitor charging coil portion 1a is short-circuited by the diode 18 to prevent the generation of a high voltage of opposite polarity in the coil portion 1a. On the other hand, the voltage generated in the other high-speed capacitor charging coil portion 1b is short-circuited through the primary winding 2a of current transformer 2, the diode 12 and the center tap 1c of the capacitor charging coil 1, thus producing an output in the secondary winding 2b of the current transformer 2. This output places the thyristor 4 in a conductive state so that the charge stored in the capacitor 6 is discharged through the thyristor 4, the ground, the primary winding 9a of the ignition coil 9, inducing a high voltage in its secondary winding 9b and thereby providing an ignition spark at the spark plug 10.

The 3b embodiment shown in FIG. 6b is substantially the same as the 3a embodiment described above except that the low-speed and high-speed capacitor charging coil portions 1a and 1b are wound on separate cores, and therefore its operation is identical with that of the 3a embodiment.

In the fourth embodiment shown in FIG. 7, a resistance coil 19 is connected in series with the low-speed and high-speed capacitor charging windings 1a and 1b, and the primary winding 2a of the current transformer 2 is connected between the ground and the center tap 1c provided in the low-speed capacitor charging winding 1a to supply a current of negative phase through a portion of the winding 1a. The capacitor charging windings 1a and 1b are wound on separate cores 13 and 14 in the same winding sense and the resistance coil 19 is wound on the core 14 in a sense opposite to that in which the windings 1a and 1b are wound. Thus, the resistance 19 serves, when the generating coil 1 is taken as a whole, to increase the resistance R alone without increasing the inductance L and thereby to decrease the time constant given by the formula $T = L/R$.

According to the fourth embodiment as described above, when the polarity of voltages generated in the capacitor charging windings 1a and 1b is reversed on the next half cycle, the generated voltage in the low-speed capacitor charging winding 1a is short-circuited by the diode 18 to thereby prevent the generation of a high voltage of opposite polarity as in the case of the third embodiment. On the other hand, the voltage generated in the high-speed capacitor charging winding 1b

is short-circuited through the primary winding 2a of the current transformer 2, the diode 12 and the center tap 1c of the low-speed capacitor charging winding 1a. This induces an output in the secondary winding 2b of the current transformer 2 and the thyristor 4 is placed in a conductive state by this secondary winding output, causing the capacitor 6 to discharge its stored charge through the thyristor 4, the ground and the primary winding 9a of the ignition coil 9 and thereby inducing a high voltage in the secondary winding 9b thereof to provide an ignition spark at the spark plug 10. Here, the reason for causing the primary current of the current transformer 2 to flow through the portion of the low-speed capacitor charging winding 1a when producing an ignition signal resides in that when the charging of the capacitor 6 by the low-speed winding 1a is completed, that is, when the generated voltage in the low-speed capacitor charging winding 1a becomes zero voltage, the counter electromotive force acting on each of the low-speed and high-speed capacitor charging windings 1a and 1b disappears altogether so that there is an increase in the flux of the low-speed capacitor charging winding 1a having a higher number of turns and there is a decrease in the flux of the high-speed capacitor charging winding 1b, thereby causing a noise voltage in the high-speed capacitor charging winding 1b having the reduced flux. Such a noise voltage may cause an erroneous operation of the thyristor 4. Such an erroneous operation can be prevented by always supplying a current in the low-speed capacitor charging winding 1a in the manner described above.

The same purpose can also be achieved by connecting the primary winding 2a of the current transformer 2 in a perfect parallel relation with the generating coil 1 as shown in the fifth and sixth embodiments shown in FIGS. 8 and 9, respectively.

While, in the second and third embodiments described above, the primary winding 2a of the current transformer 2 may be connected in parallel with the capacitor charging winding 1a or 1b as shown in FIGS. 3c, FIG. 6c and FIG. 6d, if the low-speed and high-speed capacitor charging windings 1a and 1b are wound on one and the same core, it is preferable to connect the primary winding 2a of the current transformer 2 in parallel with the high-speed capacitor charging winding 1b having a smaller number of turns and a smaller ratio L/R. On the other hand, if the low-speed and high-speed capacitor charging windings 1a and 1b are wound on separate cores, then it is preferable to connect the primary winding 2a of the current transformer 2 in parallel with the low-speed capacitor charging winding 1a having a higher number of turns from another standpoint of reducing the inverse voltage applied to the current transformer 2.

Further, in the embodiment shown in FIG. 7, the resistance coil 19 is not necessarily needed as is apparent to those skilled in the art, and moreover it is possible to provide the high-speed capacitor charging winding 1b with the center tap 1c and to connect the primary winding 2a of the current transformer 2 between the center tap 1c and the diode 3 side end of the low-speed capacitor charging winding 1a.

Still furthermore, in the embodiments shown in FIGS. 6, 7, 8 and 9, the diode 18 is provided so that at high engine speeds the output of the high-speed capacitor charging winding 1b is applied to the capacitor 6 without passing through the low-speed capacitor charg-

ing winding 1a and thus it serves the same purpose as that of the diode 11 used in the embodiments shown in FIGS. 3a and 3b. Particularly, if the generating coil 1 is wound on one and the same core as shown in FIG. 8, the diode 18 may be connected in parallel with the high-speed capacitor charging winding 1b as shown in FIG. 8 - 1. Also, in the embodiments shown in FIGS. 6a, 6b, 6c, 6d and FIG. 7, the diode 18 may be connected in parallel with the generating coil 1 as shown in FIGS. 6e, 6f, 6g, 6h and FIG. 7 - 1.

The seventh embodiment shown in FIG. 10 is particularly intended for use with multicylinder internal combustion engines having two or more cylinders. In this embodiment, when a charging current is flowing into one capacitor, the other capacitor previously placed in a charged state is caused to discharge its stored charge. The construction and operation of this embodiment as applied to a two-cylinder internal combustion engine will now be explained.

In FIG. 10, numerals 1 and 1' designate the generating coils of a magneto generator driven by the engine so that every time the engine crankshaft makes one complete rotation a single AC voltage e and e' is generated with a phase difference of 180° in the capacitor charging coils 1 and 1', respectively, as shown by the solid lines in FIGS. 12(a) and 12(b). Numerals 2 and 2' designate current transformers with the current transformer 2 comprising a primary winding 2a and a secondary winding 2b and the current transformer 2' comprising a primary winding 2a' and a secondary winding 2b'. The primary windings 2a and 2a' are connected in series with the non-grounded sides of the capacitor charging coils 1 and 1', respectively. Numerals 3 and 3' designate diodes each constituting rectifying means. Numerals 7 and 7' designate high-resistance resistors. Numerals 4 and 4' designate thyristors constituting semiconductor switching elements with the control electrodes thereof being grounded through the parallel circuits respectively comprising protective diodes 5 and 5' and the secondary windings 2b and 2b' of the current transformers 2 and 2' which are not connected to the respective anodes of the thyristors 4 and 4'. Numerals 6 and 6' designate capacitors having one end thereof respectively connected to the primary windings 2a and 2a' of the current transformers 2 and 2' through the diodes 3 and 3' and to the ground through the anode and the cathode of the thyristors 4 and 4', respectively, and the other ends are grounded by way of the parallel circuits respectively comprising diodes 8 and 8' and primary windings 9a and 9a' of ignition coils 9 and 9'. Secondary windings 9b and 9b' of the ignition coils 9 and 9' are respectively connected to spark plugs 10 and 10' provided in the respective cylinders of the engine. FIG. 14 illustrates the construction of the magneto generator G driven by the two-cylinder engine, in which numeral 20 designates a rotor connected to the crankshaft of the engine, the rotor 20 consisting of a permanent magnet 23 and magnetic poles 24, 25a and 25b which are cast and embedded in an iron shell 21 by a non-magnetic material 22, such as aluminum or synthetic resin. Numeral 26 designates a stator including iron cores 27 and 28 disposed 180° apart from each other and the capacitor charging coils 1 and 1' are wound on the cores 27 and 28, respectively.

With the construction described above, the ignition system of FIG. 10 operates as follows. When the mag-

neto generator G rotates, a voltage e of the waveform as shown by the solid line in FIG. 12(a) is generated in the capacitor charging coil 1. Then, as the voltage e begins to increase in the positive direction, a charging current I_c as shown in FIG. 12(c) is supplied to the capacitor 6 through a circuit consisting of the primary winding 2a of the current transformer 2, the diode 3, the capacitor 6, and a parallel circuit consisting of the diode 8 and the primary winding 9a of the ignition coil 9, thereby charging the capacitor 6 and producing its terminal voltage E_1 as shown by the broken line in FIG. 12(a). On the other hand, when a voltage e' having the waveform as shown by the solid line in FIG. 12(b) is generated in the capacitor charging coil 1' with a 180° phase lag and it begins to increase in the positive direction, a charging current I_c' as shown in FIG. 12(d) is supplied to the capacitor 6' through a circuit comprising the primary winding 2a' of the current transformer 2', the diode 3', the capacitor 6' and a parallel circuit consisting of the diode 8' and the primary winding 9a' of the ignition coil 9', thereby producing a terminal voltage E' of the capacitor 6' as shown by the broken line in FIG. 12(b). Then, as the charging current I_c begins to flow into the primary winding 2a' of the current transformer 2', a voltage V' as shown in FIG. 12(f) is induced in the secondary winding 2b' of the current transformer 2' and this voltage V' is applied to the control electrode of the thyristor 4. Consequently, the thyristor 4 is placed in a conductive state at a time t_1 , causing the capacitor 6 to discharge its stored charge through a circuit extending from the thyristor 4 to the primary winding 9a of the ignition coil 9. When this occurs, a high voltage is induced in the secondary winding 9b of the ignition coil 9 and therefore an ignition spark is provided at the spark plug 10. Then, as the crankshaft rotates through another 180° so that the charging current I_c shown in FIG. 12(c) begins to flow into the capacitor 6 from the capacitor charging coil 1, a voltage as shown in FIG. 12(e) is induced in the secondary winding 2b of the current transformer 2. Consequently, the thyristor 4' conducts at a time t_2 causing the capacitor 6' to discharge its stored charge through the primary winding 9a' of the ignition coil 9' to induce a high voltage in the secondary winding 9b' of the ignition coil 9' and thus to provide an ignition spark at the ignition spark 10'.

In the case of a three-cylinder internal combustion engine, three capacitor charging coils are mounted on the stator 26 of the magneto generator at regular intervals of 120° and each of the capacitor charging coils is connected in series with its respective capacitor, current transformer, ignition coil and ignition plug, so that the output of each of the current transformers is applied to the control electrode of the thyristors associated with the previously charged capacitors. In this way, the arrangement for the three-cylinder engine operates in the same manner as that described for the embodiment of FIG. 10. And this is true with the arrangements for engines having four or more cylinders.

As previously explained, the high resistance resistors 7 and 7' are provided to cause the capacitors 6 and 6' to discharge the stored charge thereof for the initial starting purposes and it will be unnecessary to mention that these resistors may be connected either in parallel with the capacitors 6 and 6' or in parallel with the thyristor 4 and 4', respectively.

The eighth embodiment shown in FIG. 11 differs from the above described seventh embodiment in that the primary windings 2a and 2a' of the current transformers 2 and 2' are connected in parallel with the capacitor charging coils 1 and 1', respectively, and diodes 12 and 12' are respectively connected in series with the primary windings 2a and 2a' of the current transformers 2 and 2' so that those half waves which are opposite in polarity to the charging half waves of the capacitor charging coils 1 and 1', are utilized to control the thyristors 4 and 4', respectively.

The operation of the eighth embodiment is as follows. When the magneto generator G rotates, a voltage e having a waveform as shown by the solid line in FIG. 13(a) is produced in the capacitor charging coil 1. Then, as the voltage e begins to increase in the positive direction, a charging current I_c as shown by the solid line in FIG. 13(c) is supplied to the capacitor 6 through a connection comprising the diode 3, the capacitor 6 and a parallel circuit consisting of the diode 8 and the primary winding 9a of the ignition coil 9, charging the capacitor 6 and thereby producing a terminal voltage E thereacross as shown by the broken line in FIG. 13(a). On the other hand, a voltage e' having a waveform as shown by the solid line in FIG. 13(b) is generated in the capacitor charging coil 1' with a phase lag of 180°. Then, as the voltage e' begins to increase in the negative direction first, a negative phase current (shown by the broken line in FIG. 13(d)) flows through a path consisting of the coil 1', the ground, the primary winding 2a' of the current transformer 2', the diode 12' and the coil 1', thereby generating a secondary output V' (FIG. 13(f)) of inverted phase in the secondary winding 2b' of the current transformer 2'. This voltage is then applied to the gate of the thyristor 4 provided for another cylinder, so that the thyristor 4 is turned on at a time t_1 , causing the capacitor 6 to discharge its stored charge through a circuit extending from the thyristor 4 to the primary winding 9a of the ignition coil 9 and thereby inducing a high voltage in the secondary winding 9b of the ignition coil 9 to deliver an ignition spark at the spark plug 10. When the crankshaft rotates further so that the voltage e' begins to build up in the coil 1' in the positive direction, a charging current I_c' as shown by the solid line in FIG. 13(d) is supplied to the capacitor 6' through the diode 3', the capacitor 6', and a parallel circuit consisting of the diode 8' and the primary winding 9a' of the ignition coil 9', producing a terminal voltage E' across the capacitor 6' as shown by the broken line in FIG. 13(b).

When the crankshaft rotates still further so that the voltage e is produced in the capacitor charging coil 1 in the negative direction at a time t_2 , the thyristor 4', is turned on by a secondary output V (FIG. 13(e)) of the current transformer 2. When this occurs, the charge on the capacitor 6', is discharged through the primary winding 9a' of the ignition coil 9', producing a high voltage in the secondary winding 9b' of the ignition coil 9' and thereby providing an ignition spark at the spark plug 10'. The diodes 5 and 5' respectively serve to block the negative-going voltage generated in the current transformers 2 and 2' to thereby protect the gate of the thyristors 4 and 4', respectively.

The ninth embodiment shown in FIG. 15 is designed for use chiefly with two cycle engines. In this embodiment, current supplied from the capacitor charging coils 1 and 1' to the primary windings 2a and 2a' of the

current transformers 2 and 2', respectively, is subjected to full-wave rectification to provide the system with a reversing preventive function (how the reversing in a two-cycle engine can take place will be explained later). Therefore, this embodiment differs from the seventh embodiment shown in FIG. 10 in that rectifying means, i.e. full-wave rectifiers 3A and 3A' respectively comprising four diodes 3a, 3b, 3c and 3d and 3a', 3b', 3c' and 3d' are provided between the capacitor charging coils 1 and 1' and the primary winding 2a and 2a' of the current transformers 2 and 2', respectively.

The operation of the embodiment of FIG. 15 is as follows. The rotation of the magneto generator G generates a voltage e having a waveform as shown by the solid line in FIG. 18(a). When this voltage e begins to increase in the negative direction, a charging current I_c as shown by the solid line front portion waveform in FIG. 18(c) is supplied to the capacitor 6 through a connection comprising the diode 3b of the full-wave rectifier 3A, the primary winding 2a of the current transformer 2, the capacitor 6, a parallel circuit consisting of the diode 8 and the primary winding 9a of the ignition coil 9 and the diode 3c of the full-wave rectifier 3A, thereby charging the capacitor 6. Then, as the voltage e in the capacitor charging coil 1 begins to increase in the positive direction, the capacitor 6 is charged further through the diodes 3a and 3d of the full-wave rectifier 3A, producing across it a terminal voltage E having a two-step waveform shown by the broken line in FIG. 18(a). On the other hand, a voltage e' having a waveform as shown by the solid line in FIG. 18(b) is generated in the capacitor charging coil 1' with a 180° phase lag. Then, as the voltage e' begins to increase in the negative direction, a charging current I_c as shown by the solid line in FIG. 18(d) is supplied to the capacitor 6' by way of the diode 3b' of the full-wave rectifier 3A', the primary winding 2a' of the current transformer 2', the capacitor 6', a parallel circuit consisting of the diode 8' and the primary winding 9a' of the ignition coil 9' and the diode 3c' of the full-wave rectifier 3A', thereby generating across the capacitor 6' a terminal voltage E' as represented by the lower front portion of the waveform shown by the broken line in FIG. 18(b). Also, when the charging current I_c begins to flow into the primary winding 2a' of the current transformer 2' through the diodes 3b' and 3c' of the full-wave rectifier 3A', a voltage V' as shown by the solid line in FIG. 18(f) is produced in the secondary winding 2b' of the current transformer 2' and this voltage V' is then applied to the control electrode of the thyristor 4. Consequently, at a time t_1 , the thyristor 4 is turned on by the first positive-going voltage in the secondary winding 2b', so that the charge stored in the capacitor 6 is discharged through a circuit extending from the thyristor 4 to the primary winding 9a of the ignition coil 9, inducing a high voltage in the secondary winding 9b of the ignition coil 9 and thus providing an ignition spark at the spark plug 10. Also, when the voltage in the capacitor charging coil 1' begins to increase in the positive direction, the capacitor 6' is charged further and its terminal voltage becomes as represented by the rear higher step portion of the waveform shown by the broken line in FIG. 18(b). As the crankshaft rotates through another 180° so that the charging current I_c as shown by the solid line in FIG. 18(e) begins to flow to the capacitor 6 from the capacitor charging coil 1, a voltage V as shown by the solid line in FIG. 18(e) is in-

duced in the secondary winding $2b$ of the current transformer 2 . Consequently, at a time t_2 the thyristor $4'$ is turned on by the first positive-going voltage in the secondary winding $2b$, causing the capacitor $6'$ to discharge its stored charge through the primary winding $9a'$ of the ignition coil $9'$ and thereby inducing a high voltage in the secondary winding $9b'$ of the ignition coil $9'$ to provide an ignition spark at the spark plug $10'$.

On the other hand, if the engine is driven in the reverse direction, then voltages e and e' as shown by the one-dot chain line in FIGS. 18(a) and 18(b), respectively, are produced in the capacitor charging coils 1 and $1'$. As a result, charging currents I_c and I_c' as shown by the broken lines in FIGS. 18(c) and 18(d) are supplied to capacitors 6 and $6'$, respectively, producing thereacross terminal voltages E and E' as shown by the twodot chain line in FIGS. 18(a) and 18(b), respectively. Simultaneously, voltages V and V' as shown by the broken line in FIGS. 18(e) and 18(f), respectively, are induced in the secondary windings $2b$ and $2b'$ of the current transformers 2 and $2'$, respectively. Consequently ignition sparks for the spark plugs 10 and $10'$ occur alternately at times t_1' and t_2' when the first positive-going voltages are induced in the secondary windings $2b$ and $2b'$. Thus, the ignition times t_1' and t_2' deviate considerably from the previously described ignition times t_1 and t_2 used for the forward running of the engine. In this way, ignition sparks are delivered to the spark plugs 10 and $10'$ at the instants when the ignition of the engine cannot take place, thereby preventing the engine from operating in the reverse direction.

In the ninth embodiment described above, the outputs of the capacitor charging coils 1 and $1'$ are subjected to full-wave rectification before they are supplied to the capacitors 6 and $6'$ and in this way the magnitude of capacitor charging voltages can be increased.

FIG. 16 illustrates a tenth embodiment of the invention in which the diodes $3a$, $3b$, $3c$ and $3d$ and the diodes $3a'$, $3b'$, $3c'$ and $3d'$ constituting the full-wave rectifiers $3A$ and $3A'$, respectively, are connected in such a manner that the outputs of the capacitor charging coils 1 and $1'$ are respectively supplied, after full-wave rectification, to the current transformers 2 and $2'$ and only the positive half wave outputs of the capacitor charging coils 1 and $1'$ are subjected to half-wave rectification and are then applied to the capacitors 6 and $6'$, respectively. In the tenth embodiment, the waveforms shown by the solid and broken lines in FIGS. 19(a) and 19(b) and the waveforms shown by the solid lines in FIGS. 19(c), 19(d), 19(e) and 19(f) correspond to those of the ninth embodiment which are employed for the forward running of an engine, and the forward running of the engine is effected in the similar manner as that of the ninth embodiment. Further, the waveforms shown by the one-dot and two-dot chain lines in FIGS. 19(a) and 19(b) and the waveforms shown by the broken lines in FIGS. 19(c), 19(d), 19(e) and 19(f) correspond to those of the ninth embodiment which are employed when the engine is driven in the reverse direction. Thus, in the similar manner as used in the ninth embodiment, the reversing of rotation of the engine can be prevented. However, FIGS. 19(c) and 19(d) show the currents I_h and I_h' which flow respectively into the primary windings $2a$ and $2a'$ of the current transformers 2 and $2'$. Also in the tenth embodiment, the required ignition signals are provided from the sec-

ondary windings $2b$ and $2b'$ of the current transformers 2 and $2'$ by means of the negative-going currents which flow through a circuit consisting of the capacitor charging coil 1 , diode $3b$, primary winding $2a$ of the current transformers 2 and the diode $3c$ and a circuit consisting of the capacitor charging coil $1'$, diode $3b'$, primary winding $2a'$ of the current transformers $2'$ and the diode $3c'$. Thus, there is no need to cause the capacitors 6 and $6'$ to discharge the stored charges thereof for the initial starting purposes and thus the resistors 7 and $7'$ employed in the ninth embodiment are eliminated.

FIG. 17 illustrates an eleventh embodiment of the invention. This embodiment differs from the tenth embodiment shown in FIG. 16 in that current subjected to full-wave rectification is supplied through a portion of the primary windings $2a$ and $2a'$ of the current transformers 2 and $2'$ to prevent reverse running of the engine. To this end, the primary windings $2a$ and $2a'$ of the current transformers 2 and $2'$ are respectively provided with center taps $2c$ and $2c'$ and the diodes $3b$ and $3b'$ are connected between the respective center taps $2c$ and $2c'$ and the ground. The operation of this embodiment will be explained hereunder.

When the magneto generator G is made to rotate, a voltage e having a waveform as shown by the solid line in FIG. 20(a) is generated in the capacitor charging coil 1 . Then, as the voltage e begins to increase in the negative direction, a short-circuit current flows through a circuit consisting of the capacitor charging coil 1 , the diode $3b$ of the full-wave rectifier $3A$, the center tap $2c$ of the current transformer 2 , the primary winding $2a$ of the current transformer 2 and the diode $3c$ of the full-wave rectifier $3A$. At the same time, a part of this short-circuit current flows into the primary winding $2a$ of the current transformer 2 through the center tap $2c$, inducing in the secondary winding $2b$ a voltage V of a limited voltage value of the left-hand first cycle as shown by the solid line in FIG. 20(e). This voltage V is then applied to the control electrode of the thyristor $4'$ provided for another cylinder, thus placing it in a conductive state. When the voltage e in the capacitor charging coil 1 begins to increase in the positive direction, the capacitor 6 is charged through a circuit comprising the diode $3a$ of the full-wave rectifier $3A$, the primary winding $2a$ of the current transformer 2 , the diode $3d$, the capacitor 6 and a parallel circuit consisting of the diode 8 and the primary winding $9a$ of the ignition coil 9 , thereby charging the capacitor 6 and producing across it a terminal voltage E of a waveform as shown by the broken line in FIG. 20(a). On the other hand, a voltage e' of a waveform as shown by the solid line in FIG. 20(b) is generated in the capacitor charging coil $1'$ with a phase lag of 180° . When this voltage begins to increase in the negative direction, a short-circuit current flows through a circuit comprising the capacitor charging coil $1'$, the diode $3b'$ of the full-wave rectifier $3A'$, the center tap $2c'$ of the current transformer $2'$, the primary winding $2a'$ and the diode $3c'$ of the full-wave rectifier $3A'$. At the same time, a portion of this short-circuit current flows into the primary winding $2a'$ of the current transformer $2'$ through the center tap $2c'$, thereby inducing in the secondary winding $2b'$ a voltage V' of a limited voltage value of the left-hand first one cycle as shown by the solid line in FIG. 20(f). This voltage V' is then applied to the control electrode of the thyristor 4 provided for another cylinder, so that the thyristor 4 is turned on at a

time t_1 by the first positive-going current flowing through the secondary winding $2b'$. This causes the capacitor 6 to discharge its stored charge through a circuit extending from the thyristor 4 to the primary winding $9a$ of the ignition coil 9, inducing a high voltage in its secondary winding $9b$ and thereby providing an ignition spark to the spark plug 10. Then, when the voltage in the capacitor charging coil 1' begins to increase in the positive direction, the capacitor 6' is charged through the diodes $3a'$ and $3d'$ of the full-wave rectifier 3A', producing across the capacitor 6' a terminal voltage E' as shown by the broken line in FIG. 20(b).

When the crankshaft rotates another 180°, the negative-going output of the capacitor charging coil 1 is short-circuited through the center tap $2c$ and the primary winding $2a$ of the current transformer 2 and the voltage V of a limited value of the first one cycle is generated in the current transformer 2 as shown by the solid line in FIG. 20(e). Consequently, the thyristor 4' provided for another cylinder is turned on at a time t_2 by the first positive-going voltage V in the secondary winding $2b$, so that the charge on the capacitor 6' is discharged by way of the primary winding $9a'$ of the ignition coil 9', inducing a high voltage in the secondary winding $9b'$ of the ignition coil 9 and thereby delivering an ignition spark at the spark plug 10'.

On the other hand, when the engine is driven in the reverse direction, voltages e and e' as shown by the one-dot chain line in FIGS. 20(a) and 20(b), respectively, are generated in the capacitor charging coils 1 and 1' and the capacitors 6 and 6' are charged by the first right-hand positive-going voltages e and e' through the diodes $3a$ and $3d$ and $3a'$ and $3d'$ of the full-wave rectifiers 3A and 3A' and the primary windings $2a$ and $2a'$ of the current transformers 2 and 2', respectively. Consequently, the terminal voltages E and E' produced across the capacitors 6 and 6', respectively, have the waveforms shown by the two-dot chain lines in FIGS. 20(a) and 20(b), respectively. In this case, the outputs of the capacitor charging coils 1 and 1' flow respectively through the capacitors 6 and 6'. Thus, while the amount of respective current flow through the primary windings $2a$ and $2a'$ of the current transformers 2 and 2' is small as compared with that which flows therethrough upon short-circuiting, the current flows through the entire lengths of the primary windings $2a$ and $2a'$ of the current transformers 2 and 2' and therefore the current ratio is large as compared to the case where current flows into a portion of the primary windings $2a$ and $2a'$ through the center taps $2c$ and $2c'$, respectively. Consequently, voltages V and V' for the right-hand first one cycle which are shown by the broken line in FIGS. 20(e) and 20(f), respectively, are generated in the secondary windings $2a$ and $2a'$ of the current transformers 2 and 2', and they have practically the same values as those of the voltages V and V' for the left-hand first one cycle under forward running condition which are shown by the solid line in FIGS. 20(e) and 20(f). Thus, at times t_1 and t_2 when the right-hand first positive-going voltages occur, the thyristors 4 and 4' are positively and alternately conducted to alternately deliver ignition sparks to the spark plugs 10 and 10' at the times t_1' and t_2' . Therefore, as shown by θ_1 in FIG. 20, the ignition times for the spark plugs 10 and 10' deviate considerably from those used under forward running conditions and ignition sparks are delivered to the spark plugs 10 and 10' at the instants

when the ignition of the engine cannot take place. In this way, the reverse running of the engine is prevented. In this case, if the diodes $3b$ and $3b'$ of the full-wave rectifiers 3A and 3A' are respectively provided between the ground and the junction points of the diodes $3a$ and $3a'$ and the primary windings $2a$ and $2a'$ of the current transformers 2 and 2', and if the current transformers 2 and 2' are not provided with the center taps $2c$ and $2c'$, then, under the forward running conditions of the engine, the first positive-going outputs of the capacitor charging coils 1 and 1' cause a flow of short-circuit current through the entire lengths of the primary windings $2a$ and $2a'$ of the current transformers 2 and 2' and induce output currents in the secondary windings $2b$ and $2b'$ thereof which are large enough to break down the thyristors 4 and 4'. For this reason, it is necessary to adjust the number of turns of the respective windings $2a$, $2b$ and $2a'$, $2b'$ of the current transformers 2 and 2' so as to reduce their current transformation ratios and thereby to reduce the value of current flow through the secondary windings $2b$ and $2b'$ to a level small enough not to break down the thyristors 4 and 4'. Consequently, when the engine is driven in the reverse direction, the first positive-going outputs generated in the capacitor charging coils 1 and 1' cause, through the capacitors 6 and 6', the first current flow through the primary windings $2a$ and $2a'$ of the current transformers 2 and 2' which is insufficient to induce in the secondary windings $2b$ and $2b'$ a large current flow sufficient to place the thyristors 4 and 4' in conductive state. Thus, when the second negative-going outputs generated in the capacitor charging coils 1 and 1' produce the positive-going voltages V and V' shown by the broken line in FIGS. 20(e) and 20(f), the thyristor 4 and 4' are alternately turned on at times t_1'' and t_2'' in FIG. 20. The result is that now the ignition timing for forward running of the engine does not deviate so much from that under reverse driven condition as shown by θ_2 in FIG. 20 and there is the danger of the engine operating in the reverse direction. In FIGS. 20(c) and 20(d), both the solid and broken lines indicate the waveforms of currents I_h and I_h' supplied to the primary windings $2a$ and $2a'$ of the current transformers 2 and 2'.

FIG. 21 illustrates a twelfth embodiment of the invention. In this embodiment, capacitor charging rectifiers 3B and 3B' (respectively corresponding to the diodes $3a$ and $3d$ and the diodes $3a'$ and $3d'$ in FIG. 17) respectively comprise only a diode $3a$ and $3a'$ which are provided between the respective current transformers 2 and 2' and the thyristors 4 and 4', while negative phase short-circuiting rectifiers 3C and 3C' (respectively corresponding to the diodes $3b$ and $3c$ and the diodes $3b'$ and $3c'$) respectively comprise a diode $3b$ and $3b'$ provided between the respective current transformers 2 and 2' and the ground. The center taps $2c$ and $2c'$ are located so that those portions of the primary windings $2a$ and $2a'$ which are on the side of the diodes $3a$ and $3a'$ have a higher number of turns than on the other portions thereof which are on the side of the diodes $3b$ and $3b'$. The capacitor charging coils 1 and 1' are provided between the respective center taps $2c$ and $2c'$ and the ground.

In the twelfth embodiment, the current transformation ratio under forward running condition of an engine when a short-circuit current is supplied to the primary windings $2a$ and $2a'$ of the current transformers 2 and

2' through the center taps 2c and 2c' by the first negative-going outputs generated in the capacitor charging coils 1 and 1', is less than the current transformation ratio under reverse driven condition when the charging currents for the capacitors 6 and 6' are supplied to the primary windings 2a and 2a' of the current transformers 2 and 2' through the center taps 2c and 2c' thereof by the first outputs generated in the capacitor charging coils 1 and 1'. Consequently, the values of the first positive secondary output currents of the current transformers 2 and 2' under forward running condition are practically the same as those of the first positive secondary output currents of the current transformers 2 and 2' under reverse driven condition, thereby positively preventing the engine from reversing its direction of rotation.

FIG. 22 illustrates a thirteenth embodiment of the system of the present invention. In this embodiment, the capacitor charging rectifiers 3B and 3B' are respectively composed of only a diode 3a and diode 3a' which are provided between the respective current transformers 2 and 2' and the thyristors 4 and 4', and the negative phase short-circuiting rectifiers 3C and 3C' are respectively composed of only a diode 3b and diode 3b' which are provided between the junction of the respective current transformers 2 and 2' and the diodes 3a and 3a' and the ground. The both ends of the secondary windings 2b and 2b' of the current transformers 2 and 2' are connected through the diodes 5a and 5b and diodes 5a' and 5b' to the control electrodes of the thyristors 4 and 4' provided for other engine cylinders. The center taps 2c and 2c' are located such that the secondary windings 2b and 2b' have a higher number of turns on those portions thereof which are on the side of the diodes 5a and 5a', than on the other portions thereof which are on the side of the diodes 5b and 5b'. The center taps 2c and 2c' are also grounded.

The thirteenth embodiment operates as follows. When the first negative-going outputs generated in the capacitor charging coils 1 and 1' under forward running condition of an engine cause a flow of short-circuit current through the primary windings 2a and 2a' of the current transformers 2 and 2' through the diodes 3b and 3b', only those portions of the secondary outputs of the current transformers 2 and 2' which flow through the center taps 2c and 2c' to the diodes 5a and 5a' are applied to the control electrodes of the thyristors 4 and 4', respectively. On the other hand, when the charging currents for the capacitors 6 and 6' are supplied to the primary windings 2a and 2a' of the current transformers 2 and 2' by way of the diodes 3a and 3a' by the outputs generated in the capacitor charging coils 1 and 1' upon driving the engine in the reverse direction, only those portions of the secondary outputs of the current transformers 2 and 2' which flow through the center taps 2c and 2c' and to the diodes 5b and 5b' are supplied to the control electrodes of the thyristors 4 and 4'. Consequently, the current transformation ratio obtainable when the first outputs are generated in the secondary windings of the current transformers 2 and 2' under forward running condition of an engine is less than that obtainable when the first outputs are generated in the secondary windings of the current transformers 2 and 2' upon driving the engine in the reverse direction, and therefore the values of the first positive secondary output current of the current transformers 2 and 2' under forward running conditions are

practically the same as those of the first positive secondary output currents of the current transformers 2 and 2' under reverse driven condition, thereby preventing the engine from operating in the reverse direction.

5 The fourteenth, fifteenth and sixteenth embodiments shown in FIGS. 23, 24 and 25, respectively, differ respectively from the eleventh, twelfth and thirteenth embodiments shown respectively in FIGS. 17, 21 and 22 in that adjusting resistors 29 and 29' are further included to adjust the turn ratios determined by the center taps 2c and 2c'.

Particularly, in the fourteenth and fifteenth embodiments, those half wave outputs of the capacitor charging coils 1 and 1' which are not used for charging the 15 capacitors 6 and 6', respectively, are caused to flow through the adjusting resistors 29 and 29' and therefore the values of their output currents are small as compared with those on short-circuiting. Consequently, no 20 delay due to any excessively large short-circuit current may be caused in the half wave outputs of the capacitor charging coils 1 and 1' for charging the capacitors 6 and 6' and a drop in their output voltages at intermediate and high engine speeds can also be reduced. In 25 other words, the relationships between the engine revolution N and the half wave output voltage V of the capacitor charging coils 1 and 1' for charging the capacitors 6 and 6', with and without the resistors 29 and 29', become as shown in FIG. 28. In this figure, the solid line curve A represents the output characteristic of the 30 capacitor charging coils 1 and 1' when the resistors 29 and 29' are employed, while the broken line curve B represents the output characteristic of the coils 1 and 1' when the resistors 29 and 29' are not employed.

FIGS. 26 and 27 illustrate seventeenth and eighteenth embodiments, respectively, which are designed to effect the stoppage of operation of an engine through the use of a simple circuitry. The seventeenth and eighteenth embodiments respectively differ from the ninth and twelfth embodiments shown in FIG. 15 and 21 in that an engine stopping switch 30 is additionally provided. The operation of these embodiments will be explained hereunder.

Firstly, the seventeenth embodiment shown in FIG. 26 operates as follows. When the magneto generator G is made to rotate, a voltage e having a waveform as shown by the solid line in FIG. 29(a) is generated in the capacitor charging coil 1. Then, as the voltage e begins to increase in the negative direction, a charging current I_c represented by the front portion of a waveform as 45 shown by the solid line in FIG. 29(c) is supplied to the capacitor 6 through a connection comprising the diode 3b of the full-wave rectifier 3A, the primary winding 2a of the current transformer 2, the capacitor 6, a parallel circuit consisting of the diode 18 and the primary winding 9a of the ignition coil 9 and the diode 3c of the full-wave rectifier 3A. When the capacitor 6 is thus charged and the voltage e in the capacitor charging coil 1 begins to increase in the positive direction, the capacitor 6 is charged further through the diodes 3a and 3d of the full-wave rectifier 3A, producing thereacross a terminal voltage E of a two-step waveform as shown by the broken line in FIG. 29(a). On the other hand, with a 50 180° phase lag, a voltage e' having a waveform as shown by the solid line in FIG. 29(b) is generated in the capacitor charging coil 1'. Then, as the voltage e' begins to increase in the negative direction, a charging current I_c' represented by the front portion of a wave-

form as shown by the solid line in FIG. 29(d) is supplied to the capacitor 6' through a connection comprising the diode 3b' of the full-wave rectifier 3A', the primary winding 2a' of the current transformer 2', the capacitor 6', a parallel circuit consisting of the diode 8' and the primary winding 9a' of the ignition coil 9' and the diode 3c' of the full-wave rectifier 3A', thereby generating across the capacitor 6' a terminal voltage E' represented by the lower first step portion of a waveform as shown by the broken line in FIG. 29(b). And, when the charging current I_c begins to flow into the primary coil 2a' of the current transformer 2' through the diodes 3b' and 3c' of the full-wave rectifier 3A', a voltage V' as shown by the solid line in FIG. 29(f) is induced in the secondary winding 2b' of the current transformer 2' and this voltage V' is applied to the control electrode of the thyristor 4. Consequently, the thyristor 4 is placed in a conductive state at a time t_1 by the first positive-going voltage in the secondary winding 2b', causing the capacitor 6 to discharge its stored charge through a circuit extending from the thyristor 4 to the primary winding 9a of the ignition coil 9 and thereby inducing a high voltage in the secondary winding 9b of the ignition coil 9 to provide an ignition spark at the spark plug 10. Then, as the voltage in the capacitor charging coil 1' begins to increase in the positive direction, the capacitor 6' is charged further through the diodes 3a' and 3d' of the full-wave rectifier 3A', producing across the capacitor 6' a terminal voltage E' represented by the higher second step portion of a waveform as shown by the broken line in FIG. 29(b). Then, as the crankshaft is rotated another 180° so that the charging current I_c as shown by the solid line in FIG. 29(c) begins to flow into the capacitor 6 from the capacitor charging coil 1, a voltage V as shown by the solid line in FIG. 29(e) is induced in the secondary winding 2b of the current transformer 2. Consequently, the thyristor 4' is turned on at a time t_2 by the first positive-going voltage in the secondary winding 2b, causing the capacitor 6' to discharge its stored charge through the primary winding 9a' of the ignition coil 9' and thereby inducing a high voltage in the secondary winding 9b' of the ignition coil 9' to provide an ignition spark at the spark plug 10'.

To stop the operation of the engine, the engine stopping switch 30 is closed. When the switch 30 is closed, the voltage e generated in the capacitor charging coil 1 begins to charge the capacitor 6 through the current transformer 2 and at the same time the capacitor 6' also begins to charge through the current transformer 2' from the thus closed engine stopping switch 30. Consequently, the secondary outputs of the current transformers 2 and 2' are applied to the control electrodes of the thyristors 4 and 4' so that the thyristors 4 and 4' are turned on causing the capacitors 6 and 6' to discharge the stored charge thereof through the respective thyristors 4 and 4' and the ignition coils 9 and 9', and at the same time the capacitor charging coil 1 is short-circuited through a parallel circuit of a circuit consisting of the engine stopping switch 30, the current transformer 2' and the thyristor 4' and a circuit consisting of the current transformer 2 and the thyristor 4. In this case, since the capacitors 6 and 6' are just starting to charge and hence their terminal voltages E and E' are still low, the voltages induced in the secondary windings 9b and 9b' of the ignition coils 9 and 9' are far from attaining the minimum values required to provide

sufficient ignition sparks at the spark plugs 10 and 10'. The capacitor charging coil 1' is also short-circuited and thus the voltage e' generated in the capacitor charging coil 1' cannot provide sufficient ignition sparks at the spark plugs 10 and 10' in the like manner as the voltage generated in the capacitor charging coil 1. Thus, the engine is brought to a stop positively.

In the seventeenth embodiment described above, it is apparent that the engine stopping switch 30 may be provided between the primary windings 2a and 2a' of the current transformers 2 and 2' and the capacitors 6 and 6' as shown by the broken line. It is also apparent that while the current transformers 2 and 2' have been shown as provided on the positive potential sides of the capacitors 6 and 6', the current transformers 2 and 2' may be provided on the negative potential sides of the latter. In the event that the current transformers 2 and 2' are provided on the negative potential sides of the capacitors 6 and 6', the engine stopping switch 30 may be provided intermediate to the charging circuits between the respective current transformers 2 and 2' and the capacitors 6 and 6'.

In the eighteenth embodiment, similarly with the seventeenth embodiment described above, that thyristor 25 which is associated with the capacitor charged first is controlled by the secondary output of the current transformers 2 and 2' and at the same time the engine stopping switch 30 is closed, so that the capacitor charging coils 1 and 1' are short-circuited and thereby 30 in sufficient ignition sparks are provided at the spark plugs 10 and 10', thus stopping the operation of the engine. While, in this embodiment, the engine stopping switch 30 is provided intermediate the charging circuits 35 for the capacitors 6 and 6' between the respective current transformers 2 and 2' and the diodes 3a and 3a', the engine stopping switch 30 may be provided between the center taps 2c and 2c' of the current transformers 2 and 2', respectively, or between the respective current transformers 2 and 2' and the diodes 3b and 3b'.

FIG. 30 illustrates a nineteenth embodiment designed for use with engines having an even-number of cylinders and employing a single capacitor for common use by two ignition units. The construction and operation of this embodiment are as follows.

Referring to FIG. 30, numeral 1 designates a first capacitor charging coil; 2 a first current transformer having its primary winding 2a connected in parallel with the first capacitor charging coil 1 through a diode 12. A capacitor 6 is adapted to be charged by the generated voltage of the first capacitor charging coil 1 in the polarity shown by the solid lines in FIG. 33. Numeral 3 designates a diode constituting a rectifying means; 4 a first bidirectional thyristor such as the Triac (commercial name) to be conducted by the positive- and negative-going generated voltages of a second current transformer which will be mentioned later. Numeral 9 designates a first ignition coil having a primary winding 9a through which the stored charge of the capacitor 6 is supplied as a discharging current upon conduction of the bidirectional thyristor 4. Numeral 10 designates a spark plug at which a spark is provided by a high voltage induced in a secondary winding 9b of the first ignition coil 9, the spark plug 10 being installed in the first cylinder of the engine which is not shown. Numeral 31 designates a first arc discharge holding diode; 32 a diode for forming a discharging circuit for the capaci-

tor 6. The component parts mentioned above constitute a first ignition unit. (However, the capacitor 6 is common for both the first ignition unit and a second ignition unit which will be explained hereunder.) Numeral 1' designates a second capacitor charging coil mounted on the stator of the magneto generator to generate a voltage having a phase difference of 180° with the generated voltage of the first capacitor charging coil 1. Numeral 2' designates a second current transformer having its primary winding 2a' connected in parallel with the second capacitor charging coil 1' through a diode 12'. The second capacitor charging coil 1' is also adapted to charge the capacitor 6 by its generated voltage in the polarity as shown by the broken lines in FIG. 33. Numeral 4' designates a second bidirectional thyristor such as the Triac (commercial name) adapted to be conducted by the positive- and negative-going generated voltages of the first current transformer 2; 9' a second ignition coil having a primary winding 9a' through which the stored charge of the capacitor 6 is supplied as a discharging current upon the conduction of the second bidirectional thyristor 4'; 10' a spark plug at which a spark is provided by a high voltage induced in a secondary winding 9b' of the ignition coil 9'. The spark plug 10' is provided in the second cylinder of the engine which is not shown. Numeral 31' is an arc discharge holding diode; 32 a diode for forming a discharging circuit for the capacitor 6. The component parts mentioned above constitute a second ignition unit.

The magneto generator used is of the type shown in FIG. 14. FIGS. 33(a), 33(b), 33(c) and 33(d) show the waveforms of the voltages e and e' and the voltages V and V' generated respectively in the capacitor charging coils 1 and 1' and the secondary windings 2b and 2b' of the current transformers 2 and 2' by the rotation of a rotor 20 of the magneto generator and the waveforms of the charging voltages E and E' applied to the capacitor 6 from the capacitor charging coils 1 and 1', respectively.

With the arrangement described above, the nineteenth embodiment of the system of the present invention operates as follows. When the rotation of the rotor of the magneto generator produces the voltage e shown in FIG. 33(a) in the first capacitor charging coil 1, the first negative-going half wave of the voltage e is supplied through the primary winding 2a of the first current transformer 2 and the diode 12, thereby inducing the one-cycle voltage V shown in FIG. 33(b) in the secondary winding 2b of the first current transformer 2. After the first negative-going half wave of the voltage V has been applied to the second bidirectional thyristor 4', the positive-going half wave of the voltage tends to be developed in the first current transformer 2. However, the time at which this positive-going half wave voltage occurs is delayed due to the current caused by the first negative-going half wave voltage. Thus, even after the appearance of the positive-going half wave of the voltage e in the first capacitor charging coil 1, the positive-going output voltage of the first current transformer 2 is continuously applied to the second bidirectional thyristor 4' maintaining it in a conductive state. Consequently, the positive-going half wave of the voltage in the first capacitor charging coil 1 charges the capacitor 6 in the polarity shown by the solid line in FIG. 33 through a circuit consisting of the diode 3, the capacitor 6, the second ignition coil 9' and

the second bidirectional thyristor 4'. Then, when the rotor of the magneto generator makes a half turn, the voltages e' and V' shown in FIGS. 33(c) and 33(d), respectively, are generated in the second capacitor charging coil 1' and the second current transformer 2', respectively. The first negative-going half wave of the voltage V' in the second current transformer 2' places the first bidirectional thyristor 4 in a conductive state, so that the capacitor 6 discharges its stored charge through the primary winding 9a of the first ignition coil 9, the first bidirectional thyristor 4 and the diode 32', inducing a high voltage in the secondary winding 9b of the first ignition coil 9 and thereby igniting the first cylinder by means of the first spark plug 10. The first bidirectional thyristor 4 is held in a conductive state by the positive-going output voltage of the second current transformer 2' continuing to be present even after the appearance of the positive-going half wave of the voltage e' in the second capacitor charging coil 1' and thus the capacitor 6 is charged through the diode 3' in the polarity shown in FIG. 33 by the positive-going half wave of the voltage in the second capacitor charging coil 1'. When the rotor makes another half turn thereby producing again the voltages e and V in the first capacitor charging coil 1 and the first current transformer 2, the negative-going half wave of the voltage V in the first current transformer 2 places the second bidirectional thyristor 4' in a conductive state, causing the capacitor 6 to discharge its stored charge through the primary winding 9a' of the second ignition coil 9', the second bidirectional thyristor 4' and the diode 32 and thereby inducing a high voltage in the secondary winding 9b' of the second ignition coil 9' to ignite the second cylinder by means of the second spark plug 10'. On the other hand, the second bidirectional thyristor 4' is retained in its conductive state by the positive-going half wave of the voltage V in the first current transformer 2 and thus the capacitor 6 is charged in the polarity shown by the solid line in FIG. 33 by the positive-going half wave of the voltage in the first capacitor charging coil 1. This process is repeated to provide ignition sparks to the respective cylinders to ensure one ignition per revolution at 180° intervals.

It is apparent that the above described nineteenth embodiment may be adapted for use with a four-cylinder engine, if the secondary windings 9b and 9b' of the first and second ignition coils 9 and 9' are respectively connected in series with two spark plugs to simultaneously provide sparks at such two spark plugs.

FIG. 31 illustrates a twentieth embodiment of the present invention. This embodiment differs from the previously explained nineteenth embodiment in that the bidirectional thyristors 4 and 4' are replaced with two ordinary unidirectional thyristors and that the outputs of the current transformers 2 and 2', respectively, are subjected to full-wave rectification by respective full-wave rectifiers 33 and 34 each consisting of four diodes connected to form a bridge circuit and the thus rectified outputs are applied to the unidirectional thyristors 4 and 4'. Therefore, the operation of this embodiment is identical with that of the nineteenth embodiment.

In the twenty-first embodiment shown in FIG. 32, similarly with the twentieth embodiment shown in FIG. 31, the ordinary unidirectional thyristors 4 and 4' are employed, and the secondary windings 2b and 2b' of

the current transformers 2 and 2' are respectively provided with the center taps 2c and 2c' which are placed at practically the midpoint of the windings of the respective secondary windings 2b and 2b'. The center taps 2c and 2c' are also grounded. Thus, the outputs alternately produced across the terminals of the current transformers 2 and 2' are rectified by the diodes 5a and 5b and the diodes 5a' and 5b', respectively, so as to be applied to the thyristors 4 and 4'. Thus, the operation of this embodiment is identical with that of the nineteen embodiment.

The twenty-second embodiment shown in FIG. 34 is still another embodiment of the present invention employing a single capacitor adapted for common use by two ignition units. This embodiment employs a two-pole magneto generator and its operation is as follows.

The capacitor charging coils 1 and 1' are arranged so that the polarity of voltages generated in one coil is opposite to that of voltages generated in the other coil. When a positive-going voltage begins to build up in the capacitor charging coil 1 as shown by the solid line arrow in the figure and a negative-going voltage begins to build up in the other capacitor charging coil 1' as shown by the broken line arrow, a short-circuit current is caused to flow through a circuit comprising the capacitor charging coil 1', the ground, the primary winding 2a' of the current transformer 2' and the diode 12', thereby inducing a voltage in the secondary winding 2b' of the current transformer 2'. This induced voltage then places the thyristor 4' through the diode 5', so that the capacitor 6 which has previously been charged in the polarity as shown (by the solid line + and - signs) is caused to discharge its stored charge through a circuit consisting of the primary windings 9a' of the ignition coil 9', the thyristor 4', the ground and the diode 32, inducing a high voltage in the secondary winding 9b' of the ignition coil 9' and thereby providing an ignition spark at the spark plug 10'. On the other hand, the positive voltage generated in the capacitor charging coil 1 charges the capacitor 6 in a direction (in the polarity shown by the broken line) opposite to that of the previous charging through a circuit consisting of the diode 3, the capacitor 6, the primary winding 9a' of the ignition coil 9', the thyristor 4' and the ground. Then, when a negative-going voltage begins to build up in the capacitor charging coil 1 as shown by the broken line arrow in the figure and a positive-going voltage begins to build up in the capacitor charging coil 1' as shown by the solid line arrow, a short-circuit current is caused to flow through the capacitor charging coil 1, the ground, the primary winding 2a of the current transformer 2 and the diode 12. Consequently, the thyristor 4 is placed in a conductive state by the output of the secondary winding 2b of the current transformer 2 through the diode 5 and thus the capacitor 6 is caused to discharge the charge stored therein (in the polarity shown by the broken line) through a circuit consisting of the primary winding 9a of the ignition coil 9, the thyristor 4, the ground and the diode 32', thereby inducing a high voltage in the secondary winding 9b of the ignition coil 9 and providing an ignition spark at the spark plug 10. On the other hand, the generated voltage of the capacitor charging coil 1' charges the capacitor 6 in the polarity shown by the solid line through a circuit consisting of the diode 3', the capacitor 6, the primary winding 9a of the ignition coil 9, the thyristor 4 and the

ground. Repetitions of the process described alternately provide ignition sparks at the spark plugs 10 and 10'. The purpose of diodes 8 and 8' is to make the arc duration time longer.

The magneto generator G employed in the twenty-second embodiment described is of the type constructed as shown in FIG. 35. As will be seen from the figure, a rotor 20 comprises two permanent magnets 23 and 23' located at opposed positions and the magnets 23 and 23' are, together with magnet pole pieces 24 and 24', cast and embedded in an iron shell 21 by a non-magnetic material 22. A stator 26 comprises two iron cores 27 and 28 arranged at opposed positions and the capacitor charging coils 1 and 1' are respectively wound on the cores 27 and 28 in the opposed senses.

In the embodiments shown in FIGS. 11, 30, 31, 32 and 34, the connections of the capacitor charging coils 1 and 1' with the current transformers 2 and 2' may be changed as shown in FIGS. 36a to 36f in which numerals 1a, 1a', 1b, 1b', 18 and 18' designate those which are identical both in construction and function to the high-speed capacitor charging coil 1a, the low-speed capacitor charging coil 1b and the diode 18, respectively, which are shown in FIGS. 6a, 6b, 8 and 9.

FIGS. 37a and 37b show 23a and 23b embodiments employing a two-pole magneto generator and a single capacitor charging coil designed for common use by two ignition units.

The embodiment of FIG. 37a operates as follows. The capacitor charging coil 1 is such that a one-cycle-per-revolution AC voltage is generated therein. Now, when a voltage begins to build up in the capacitor charging coil 1 in the direction shown by the solid line arrow, the capacitor 6 is charged by way of a circuit comprising the capacitor charging coil 1, the diode 3, the capacitor 6, a parallel circuit consisting of the diode 8 and the primary winding 9a of the ignition coil 9, the ground, the primary winding 2a' of the current transformer 2' and the diode 12'. Consequently, the thyristor 4' is turned on through the protective diode 5' by the voltage induced in the secondary winding 2b' of the current transformer 2', causing the capacitor 6' to discharge its previously stored charge through the thyristor 4', the ground and the primary winding 9a' of the ignition coil 9' and thereby inducing a high voltage in the secondary winding 9b' of the ignition coil 9' to provide an ignition spark at the spark plug 10'. Then, when the generated voltage of the capacitor charging coil 1 changes its polarity and begins to increase in the direction shown by the broken line arrow, the capacitor 6' is charged through a circuit comprising the capacitor charging coil 1, the diode 3', the capacitor 6', a parallel circuit consisting of the diode 8' and the primary winding 9a' of the ignition coil 9', the ground, the primary winding 2a of the current transformer 2 and the diode 12. Consequently, the thyristor 4 is turned on through the protective diode 5 by the voltage then generated in the secondary winding 2b of the current transformer 2, causing the capacitor 6 to discharge its previously stored charge through the thyristor 4, the ground and the primary winding 9a of the ignition coil 9 and thereby inducing a high voltage in the secondary winding 9b of the ignition coil 9 to provide an ignition spark at the spark plug 10. This process is repeated to alternately provide ignition sparks at the spark plugs 10 and 10'. The diodes 8 and 8' serve to extend the arc dura-

tion time and the resistors 7 and 7' are discharging high-resistance type resistors.

The 23b embodiment shown in FIG. 37b is substantially the same as the 23a embodiment described above except that the location of the current transformers 2 and 3 are different from those of the 23a embodiment.

The magneto generator G employed in both the 23a and 23b embodiments is constructed as shown in FIG. 38. In other words, a rotor 20 comprises two permanent magnets 23 and 23' which are arranged in opposition to each other and, together with magnetic pole pieces 24 and 24', cast and embedded in an iron shell 21 by a non-magnetic material 22. A stator 26 comprises an iron core 27 and the capacitor charging coil 1 is wound on the core 27 so that the AC voltage of one cycle per revolution of the rotor 20 is generated in the capacitor charging coil 1.

While, in the embodiments of the present invention so far described, the current transformers 2 and 2' are employed as transformers, voltage transformers may also be employed as transformers, particularly in the embodiments shown in FIGS. 3a and 3b, FIGS. 6a and 6b, FIGS. 7, 8, 9, 11, 30, 31, 32 and 34.

The twenty-fourth to twenty-seventh embodiments shown in FIGS. 39 to 42 are particularly designed for use with multicylinder engines having three or more cylinders. These embodiments are designed so that when a capacitor charging current is caused to flow into one of the charging circuits, those thyristors which are provided in two discharging circuits corresponding to the remaining charging circuits are controlled to produce an ignition voltage in the selected one of the ignition coils. In this way, when applied to a two cycle engine, these embodiments can prevent the engine from operating in the reverse direction.

Referring now to FIG. 39 illustrating the twenty-fourth embodiment designed for use on a three cylinder engine, numerals 1, 2 and 3 designate the capacitor charging coils of a magneto generator G driven by the engine so that the AC voltages e_1 , e_2 and e_3 shown by the solid lines in FIGS. 45(a), 45(b) and 45(c), respectively, are generated in the coils 1, 2 and 3, respectively, at 120° intervals and once for each revolution of the engine crankshaft. Numerals 4, 5 and 6 designate current transformers respectively having, as shown in FIG. 43, two primary windings 4a and 4b, 5a and 5b, and 6a and 6b, and one secondary winding 4c, 5c and 6c, with the primary windings 4a and 4b, 5a and 5b, and 6a and 6b being connected in series with the non-grounded sides of the capacitor charging coils 1, 2 and 3, respectively. Numerals 7, 8 and 9 designate diodes; 10, 11 and 12 Zener diodes; 13, 14 and 15 thyristors constituting semiconductor switching elements having the respective control electrodes thereof grounded through the respective parallel circuits consisting of protective diodes 16, 17 and 18, respectively, and the secondary windings 6c, 4c and 5c of the current transformers 6, 4 and 5, respectively, which are not connected to the respective anodes of the thyristors 13, 14 and 15. Numerals 19, 20 and 21 designate capacitors having one end thereof respectively connected to the primary windings 5b, 6b and 4b of the current transformers 5, 6 and 4 by way of the diodes 7, 8 and 9 and through the Zener diodes 10, 11 and 12, respectively. The one end of the capacitors 19, 20 and 21 are also grounded respectively through the anodes and the

cathodes of the thyristors 13, 14 and 15, respectively, and the other ends are grounded through the associated parallel circuits respectively comprising diodes 22, 23 and 24 and primary windings 25a, 26a and 27a of ignition coils 25, 26 and 27. Secondary windings 25b, 26b and 27b of the ignition coils 25, 26 and 27 are respectively connected to spark plugs P_1 , P_2 and P_3 provided in the respective cylinders of the engine. Resistors 28, 29 and 30 are connected in parallel across the anode 10 and cathode of the thyristors 13, 14 and 15, respectively.

FIG. 46 illustrates the construction of a magneto generator driven by a three-cylinder engine. In the figure, numeral 31 designates a rotor connected to the crank-shaft of an engine and comprising a permanent magnet 34 and magnetic poles 35, 36a and 36b which are cast and embedded in an iron shell 32 by a non-magnetic material 33 such as aluminum. Numeral 37 designates a stator comprising iron cores 38, 39 and 40 located at 15 positions which are displaced by 120° from each other. The capacitor charging coils 1, 2 and 3 are wound on the cores 38, 39 and 40, respectively.

With the arrangement described above, the operation of this embodiment will be explained hereunder.

When the magneto generator G is made to rotate, a voltage having a wave-form as shown by the solid line in FIG. 45(a) is generated in the capacitor charging coil 1. Then, when this voltage begins to increase in the positive direction (at time t_1), a charging current I_1 as 20 shown in FIG. 45(d) is supplied through the primary windings 4a and 5b of the current transformers 4 and 5, the diode 7, the Zener diode 10, the capacitor 19 and a parallel circuit consisting of the diode 22 and the primary winding 25a of the ignition coil 25, thereby charging the capacitor 19 and producing thereacross a terminal voltage E_1 as shown by the broken line in FIG. 45(d). On the other hand, with a 180° phase lag, a voltage e_2 having a waveform as shown by the solid line in FIG. 45(d) is generated in the capacitor charging coil 20. Then, when this voltage begins to increase in the positive direction, a charging current I_2 as shown in FIG. 45(e) is supplied through the primary windings 5a and 6b of the current transformers 5 and 6, the diode 8, the Zener diode 11, the capacitor 20 and a parallel circuit 25 consisting of the diode 23 and the primary winding 26a of the ignition coil 26, thereby producing across the capacitor 20 a terminal voltage E_2 as shown by the broken line in FIG. 45(b). On the other hand, when the charging current I_2 begins to flow through the primary windings 5a and 6b of the current transformers 5 and 6 (i.e. at a time t_2), voltages E_5 and E_6 as shown by the solid line in FIGS. 45(h) and 45(i), respectively, are respectively induced in the secondary windings 5c and 6c of the current transformers 5 and 6. The voltage E_5 is applied to the control electrode of the thyristor 15 and the voltage E_6 is applied to the control electrode of the thyristor 13, thereby breaking the thyristors 15 and 13 into conduction. Consequently, the capacitor 19 is caused to discharge its stored charge through a circuit extending from the thyristor 13 to the primary winding 25a of the ignition coil 25, inducing a high voltage in the secondary winding 25b of the ignition coil 25 and thereby providing an ignition spark at the spark plug P_1 . In this case, since the capacitor 21 has no charge previously stored therein, the conduction of the thyristor 15 does not result in discharging of any stored charge and hence no high voltage is induced in the secondary

winding 27b of the ignition coil 27. In other words, at the time t_2 , a high sparking voltage is produced in the ignition coil 25 only. As the crankshaft is rotated an additional 120° so that a charging current I_3 as shown in FIG. 45(f) is caused to flow to the capacitor 21 by the capacitor charging coil 3 (i.e. at a time t_3), voltages E_6 and E_4 as shown by the solid line in FIGS. 45(i) and 45(g), respectively, are generated in the secondary windings 6c and 4c of the current transformers 6 and 4, thereby breaking the thyristors 13 and 14 into conduction. In this case, however, the capacitor 19 has previously discharged at the time t_2 and therefore it discharges no stored charge. Thus, upon the conduction of the thyristor 14, the capacitor 20 is caused to discharge its stored charge through the primary winding 26a of the ignition coil 26, inducing a high voltage in its secondary winding 26b and thereby providing an ignition spark at the plug P_2 . When the crankshaft is rotated a still another 120° so that the charging current I_1 as shown in FIG. 45(d) is caused to start flowing to the capacitor 19 by the capacitor charging coil 1 (i.e. at a time $t_4 = t_1$), voltages E_4 and E_5 as shown by the solid line in FIGS. 45(g) and 45(h), respectively, are generated in the respective secondary windings 4c and 5c of the current transformers 4 and 5, thereby breaking the thyristors 14 and 15 into conduction. In this case, however, the capacitor 20 has no charge stored therein, since it has previously discharged its stored charge at the time t_3 . Thus, the conduction of the thyristor 15 causes the capacitor 21 to discharge its stored charge through the primary windings 27a of the ignition coil 27, inducing a high voltage in the secondary winding 27b of the ignition coil 27 and thereby providing an ignition spark at the spark plug P_3 . In other words, the charge stored in the capacitor 19 by the capacitor charging coil 1 is discharged at the time t_2 when the capacitor charging coil 2 starts charging and this discharging of the stored charge induces a high voltage in the ignition coil 25, while the charge stored in the capacitor 20 by the capacitor charging coil 2 is discharged at the time t_3 at which the charging by the capacitor charging coil 3 begins, thereby inducing a high voltage in the ignition coil 26. While on the other hand, at the time t_1 when the capacitor charging coil 1 starts charging, the charge stored in the capacitor 21 by the capacitor charging coil 3 is discharged to induce a high voltage in the ignition coil 27.

It will thus be seen that by providing as many capacitor charging coils, current transformers, ignition coils and thyristors as there are cylinders, by causing current transformers to produce ignition signals for discharging the previously stored charge in capacitors simultaneously with the charging of another capacitors and by associating the charging of capacitors by capacitor charging coils with the generation of ignition signals by current transformers, any suitable ignition system for multicylinder engines can be provided.

Now considering the ignition timing of a two-cycle engine with reference to FIG. 47 in which the direction of rotation of the engine is shown as clockwise and the top dead center is indicated at the top of the graph, an ignition timing which has been generally considered proper is one in which an ignition spark is caused to occur at the spark plug at some point within the range θ_1 , i.e. between the top dead center and a point about 25° before the top dead center. Assume now that the engine is driven in the reverse direction (counterclock-

wise) by chance. In this case, if the ignition spark is allowed to occur at some point within the range θ_2 of about 90° with respect to the top dead center, i.e. between a point 65° before the top dead center and a point 25° after the top dead center under reverse driven condition, the engine will be kept rotating in the reverse direction, thus giving rise to a serious drawback in practice.

The foregoing difficulty is overcome by the present invention. In the embodiment shown in FIG. 39, at the same time when a charging current is supplied to the capacitor 19 by the capacitor charging coil 1, the current transformers 4 and 5 supply ignition timing signals to the thyristors 14 and 15 connected to the other capacitors 20 and 21. Similarly, with other capacitor charging coils 2 and 3, ignition timing signals are supplied to thyristors other than those which are connected to the capacitors being charged by the coils 2 and 3.

Assuming now that the engine is driven in the reverse direction, the polarity of a voltage then generated in the capacitor charging coil 1 is opposite to that shown by the solid line in FIG. 45(a) and thus the capacitor 19 is charged by the negative-going voltages shown in FIG. 45(a). The charging voltage applied to the capacitor 19 at that time is shown by the one-dot chain line in FIG. 45(a). Since there are two negative voltages, the capacitor 19 is charged in steps. The charge thus stored in the capacitor 19 is discharged to produce an ignition voltage in the ignition coil 25, when the thyristor 13 is turned on by a voltage induced in the secondary winding 6c of the current transformer 6 at a time t_3' at which the next capacitor charging coil 3 begins to charge the capacitor 21. Thus, the angular difference θ_2' between the ignition time t_3' under reverse driven condition and the ignition time t_2 under forward running condition deviates sufficiently from the range θ_2 in which the two-cycle engine tends to be kept rotating in the reverse direction.

While the resistors 28, 29 and 30 respectively serve to discharge the charge stored in the capacitors 19, 20 and 21 for initial starting purposes, these resistors may be connected in parallel with the capacitors 19, 20 and 21, respectively, or alternately they may be connected in parallel with the diodes 7, 8 and 9, respectively.

The Zener diodes 10, 11 and 12 serve to prevent the occurrence of ignition signals in the secondary windings of the current transformers 4, 5 and 6, when the reverse charged charges in the capacitors 19, 20 and 21 are respectively discharged through the diodes 22, 23 and 24, the capacitor charging coils 1, 2 and 3, the primary windings of the current transformers 4, 5 and 6 and the diodes 7, 8 and 9. However, instead of the Zener diodes 10, 11 and 12, as in the twenty-fifth embodiment shown in FIG. 40, a common Zener diode 31 may be provided between the ground and the common junction point of the grounded sides of the capacitor charging coils 1, 2 and 3.

Further, while, in the embodiment shown in FIG. 39, current transformers each having two primary windings and a single secondary winding are employed and two current transformers have their one primary windings connected in the same single capacitor charging circuit, it is possible to employ current transformers 4, 5 and 6 respectively having, as shown in FIG. 44, a single primary coil 4a, 5a and 6a and two secondary windings 4c and 4c', 5c and 5c' and 6c and 6c' and to arrange the

current transformers 4, 5 and 6 so that the primary windings 4a, 5a and 6a are provided in the respective capacitor charging circuits as shown in the twenty-sixth embodiment of FIG. 41 and every two of the current transformers have one primary windings thereof connected in series with the gate circuit of the thyristors 13, 14 and 15, respectively. Alternately, as shown in the twenty-seventh embodiment of FIG. 42, it is possible to employ current transformers 4, 5 and 6 respectively including a single primary winding 4a, 5a and 6a and a single secondary winding 4c, 5c and 6c and current transformers 4', 5' and 6' respectively including a single primary winding 4a', 5a' and 6a' and a single secondary winding 4b', 5b' and 6b' and to connect these current transformers as shown in FIG. 42.

While the arrangements of the present invention as applied to a three-cycle engine have been explained, it is also possible to apply the present invention to multi-cylinder engines having four or more cylinders. In this case, it is necessary to provide, for example, at least four capacitor charging circuits each comprising at least a capacitor charging coil and a capacitor connected in series, at least four capacitor discharging circuits each comprising at least one of the capacitors, a primary winding of an ignition coil and a thyristor connected in series, and at least four current transformers each having two primary windings and one secondary winding. These component parts are then connected according to the arrangement shown in FIG. 39 so that the first capacitor charging circuit is connected to the first primary windings of the first and second current transformers, the second capacitor charging circuit is connected to the second primary winding of the second current transformer and the first primary winding of the third current transformer, the third capacitor charging circuit is connected to the second primary winding of the third current transformer and the first primary winding of the fourth current transformer, and the final *n*th capacitor charging circuit is connected to the second primary winding of the *n*th current transformer and the second primary winding of the first current transformer. It is also necessary to connect the secondary windings of the current transformers to the thyristors in the capacitor charging circuits so that the difference θ_2 in ignition time under forward and reverse running conditions sufficiently deviates from the previously explained range θ_2 in which the two-cycle engine tends to be kept rotating in the reverse direction. It is also apparent that when applied to engines having four or more cylinders, current transformers each having three primary windings may be employed to connect one of the primary windings of each of *n* - 1 current transformers in the respective capacitor charging circuits so that in the similar manner as in the embodiment of FIG. 39, when one of the capacitors supplies a charging current to one capacitor, all the thyristors connected to the other capacitors are simultaneously conducted.

It is also possible to change the positions of capacitors with those of thyristors. In this case, the diodes 22, 23 and 24 can be eliminated.

Further, in the embodiments of the present invention described and shown in FIGS. 1, 10, 15, 26 and 39 through 42, primary windings of current transformers may be connected in charging circuits which overlap discharging circuits. In this case, a diode may preferably be connected in parallel with such primary winding

to prevent the primary winding from interfering the discharge.

What we claim is:

1. An ignition system for internal combustion engines comprising: at least one charging circuit including a series combination of a capacitor charging coil for generating an output by the rotation of a permanent magnet, rectifying means for rectifying the generated output of said capacitor charging coil, and a capacitor, the flow of current in said charging circuit being directed from said capacitor charging coil to said capacitor through said rectifying means; at least one discharging circuit including said capacitor and a thyristor having a gate and connected in series with said capacitor so that said capacitor is caused to discharge its stored charge upon conduction of said thyristor; at least one ignition coil having a primary winding and a secondary winding; and at least one transformer having at least one primary winding and one secondary winding with said primary winding being electrically connected to said capacitor charging coil to detect the generated output thereof, wherein the primary winding of said ignition coil is connected to form said discharging circuit, wherein at least one spark plug is connected to the secondary winding of said ignition coil, and wherein the secondary winding of said transformer is electrically connected to the gate of said thyristor.
2. An ignition system for internal combustion engines comprising: a plurality of charging circuits each thereof including a series combination of a capacitor charging coil for generating an output by the rotation of a permanent magnet, rectifying means for rectifying the generated output of said capacitor charging coil, and a capacitor, the flow of current in each said charging circuit being directed from said capacitor charging coil to said capacitor through said rectifying means; a plurality of discharging circuits each thereof including said capacitor in one of said plurality of charging circuits and a thyristor having a gate and connected in series with said capacitor so that said capacitor is caused to discharge its stored charge upon conduction of said thyristor; a plurality of ignition coils each thereof having a primary winding and a secondary winding; and a plurality of transformers each thereof having at least one primary winding and secondary winding with said primary winding being electrically connected to one of said capacitor charging coils associated therewith to detect the generated output thereof, wherein the primary winding of each of said plurality of ignition coils is connected to form one of said plurality of discharging circuits associated therewith, wherein at least one spark plug is connected to the secondary winding of said each ignition coil, and wherein the secondary winding of said each transformer is electrically connected to the gate of the thyristor in one of said plurality of discharging circuits associated with one of said plurality of charging circuits in which the capacitor charging coil is not electrically connected to the primary winding associated with said secondary winding.
3. An ignition system for internal combustion engines comprising: a first charging circuit including a series combination of a first capacitor charging coil for generating an output by the rotation of a permanent magnet, first rectifying means for rectifying the generated output of said capacitor charging coil, a capacitor, and a first thyristor having a gate to control the charging and

discharging of said capacitor, the flow of current in said first charging circuit being directed from said first capacitor charging coil to said first thyristor through said first rectifying means and said capacitor; a second charging circuit including a series combination of a second capacitor charging coil for generating an output by the rotation of a permanent magnet, second rectifying means for rectifying the generated output of said second capacitor charging coil, said capacitor and a second thyristor having a gate to control the charging and discharging of said capacitor, the flow of current in said second charging circuit being directed from said second capacitor charging coil to said second thyristor through said second rectifying means and said capacitor to charge said capacitor in opposition to the polarity with which said capacitor is charged by said first charging circuit; a first discharging circuit including a series combination of said capacitor, said first thyristor and a first diode to discharge the charge stored in said capacitor by said second charging circuit through said first thyristor and said first diode; a second discharging circuit including a series combination of said capacitor, said second thyristor and a second diode to discharge the charge stored in said capacitor by said first charging circuit through said second thyristor and said second diode; first and second transformers each thereof having at least one primary winding and secondary winding the primary windings of said first and second transformers being respectively electrically connected to said first and second capacitor charging coils to detect the generated outputs thereof; and first and second ignition coils each thereof having a primary winding and a secondary winding, wherein the primary windings of said first and second ignition coils are respectively connected to form said first and second discharging circuits, wherein at least one spark plug is connected to the secondary winding of said first and second ignition coils, respectively, and wherein the secondary windings of said first and second transformers are respectively electrically connected to the gates of said first and second thyristors.

4. An ignition system according to claim 1, wherein the primary winding of said transformer is connected in parallel with said capacitor charging coil, and wherein a diode is connected in series with the primary winding of said transformer to pass therethrough only those half voltage waves of said capacitor charging coil which are opposite in polarity to the charging half voltage waves thereof.

5. An ignition system according to claim 2, wherein, in said each charging circuit, the primary winding of said transformer is connected in parallel with said capacitor charging coil, and wherein a diode is connected in series with said primary winding of said transformer to pass therethrough only those half voltage waves of said capacitor charging coil which are opposite in polarity to the charging half voltage waves thereof.

6. An ignition system according to claim 3, wherein the primary windings of said first and second transformers are respectively connected in parallel with said first and second capacitor charging coils, and wherein the primary windings of said first and second transformers are respectively connected in series with diodes, so that only those half voltage waves of said first and second capacitor charging coils, which are opposite in polarity to the charging half voltage waves thereof, may pass through said diodes.

7. An ignition system according to claim 1, wherein said transformer consists of a current transformer having its primary winding connected to form said charging circuit.

5 8. An ignition system according to claim 2, wherein, in each said charging circuit, said transformer consists of a current transformer having its primary winding connected to form said charging circuit.

9. An ignition system according to claim 1, wherein said capacitor charging coil consists of two coil portions connected in such a manner that the respective voltages induced in said coil portions are added together, wherein the primary winding of said transformer is connected in parallel with one of said coil portions, and wherein a diode is connected in series with the primary winding of said transformer to pass therethrough only those half voltage waves of said coil portions which are opposite in polarity to the charging half voltage waves thereof.

20 10. An ignition system according to claim 2, wherein, in each said charging circuit, said capacitor charging coil consists of two coil portions connected in such a manner that respective voltages induced in said coil portions are added together, wherein the primary winding of said transformer is connected in parallel with one of said coil portions, and wherein a diode is connected in series with the primary winding of said transformer to pass therethrough only those half voltage waves of said coil portions which are opposite in polarity to the charging half voltage waves thereof.

25 11. An ignition system according to claim 3, wherein each of said first and second capacitor charging coils comprises two coil portions connected in such a manner that respective voltages induced in said two coil portions are added together, wherein the primary winding of each of said first and second transformers is connected in parallel with one of said two coil portions associated therewith, and wherein a diode is connected in series with the primary winding of each of said first and second transformers to pass therethrough only those half voltage waves of said coil portions which are opposite in polarity to the charging half voltage waves thereof.

30 40 12. An ignition system according to claim 9, wherein said two coil portions of said capacitor charging coil are wound on one and the same core with the first coil portion having a higher number of turns than that of the second coil portion, and wherein the primary winding of said transformer is connected in parallel with said second coil portion of said capacitor charging coil.

45 55 13. An ignition system according to claim 10, wherein said two coil portions of said capacitor charging coil are wound on one and the same core with the first coil portion having a higher number of turns than that of the second coil portion, and wherein the primary winding of said transformer is connected in parallel with said second coil portion of said capacitor charging coil.

60 65 14. An ignition system according to claim 11, wherein said two coil portions of said first and second capacitor charging coils are respectively wound on one and the same core with the first coil portion having a higher number of turns than that of the second coil portion, wherein the primary windings of said first and second transformers are respectively connected in parallel

with said second coil portions of said first and second capacitor charging coils.

15. An ignition system according to claim 9, wherein said coil portions of said capacitor charging coil are wound on separate magnetically parallel cores with the first coil portion having a higher number of turns than that of the second coil portion, and wherein the primary winding of said transformer is connected in parallel with said first coil portion.

16. An ignition system according to claim 10, wherein said coil portions of said capacitor charging coil are wound on separate magnetically parallel cores with the first coil portion having a high number of turns than that of the second coil portion, and wherein the primary winding of said transformer is connected in parallel with said first coil portion of said capacitor charging coil.

17. An ignition system according to claim 11, wherein said coil portions of said first and second capacitor charging coils are respectively wound on separate magnetically parallel cores with the first coil portion having a higher number of turns than that of the second coil portion, and wherein the primary windings of said first and second transformers are connected in parallel with said first coil portions of said first and second capacitor charging coils, respectively.

18. An ignition system according to claim 2, wherein, in each said charging circuit, the primary winding of said transformer consists of first and second winding portions, wherein said first winding portion is connected to form said charging circuit between said capacitor charging coil and said rectifying means and said second winding portion is connected in parallel with said capacitor charging coil, wherein a diode is connected in series with said second winding portion to pass therethrough only those half voltage waves of said capacitor charging coil which are opposite in polarity to the charging half voltage waves thereof, and wherein said first and second winding portions of said transformer primary winding are arranged to induce voltages of the same polarity in the secondary winding of said transformer.

19. An ignition system according to claim 8, wherein the primary winding of said current transformer is provided with a center tap, wherein one end of said primary winding is connected to one end of said capacitor charging coil through the cathode and the anode of a first diode and the other end of said primary winding is connected to said one end of said capacitor charging coil through the anode and the cathode of a second diode, and wherein said center tap is connected to the other end of said capacitor charging coil through the cathode and the anode of a third diode.

20. An ignition system according to claim 8, wherein the primary winding of said current transformer is connected between one end of said capacitor charging coil and said rectifying means, wherein the secondary winding of said current transformer is provided with a center tap which divides said secondary winding into a first portion having a large number of turns and a second portion having a small number of turns, wherein the ends of said transformer secondary winding are interconnected through respective diodes and the junction point of said ends is electrically connected to the gate of said thyristor, wherein said center tap is connected to the cathode of said thyristor, and wherein the junction point between the primary winding of said current

transformer and said rectifying means is connected to the other end of said capacitor charging coil through the cathode and the anode of a diode.

21. An ignition system according to claim 8, wherein, in each said charging circuit, said rectifying means consist of four rectifying diodes for subjecting an AC output of said capacitor charging coil to full-wave rectification and supplying the resultant rectified output to the primary winding of said current transformer and said capacitor.

22. An ignition system according to claim 8, wherein, in each of said charging circuits, the secondary winding of said current transformer is provided with a center tap, wherein one end of said secondary winding is connected to the gate of said thyristor through a rectifying diode and the other end of said secondary winding is connected to the gate of said thyristor through a rectifying diode and an adjusting resistor, and wherein said center tap is connected to the cathode of said thyristor.

23. An ignition system according to claim 18, wherein said first primary winding portion of said transformer has a higher number of turns than that of said second primary winding portion.

24. An ignition system according to claim 8, wherein, in each of said charging circuits, the ends of said capacitor charging coil are connected to one end of the primary winding of said current transformer through the anode and the cathode of respective diodes, and wherein the other end of the primary winding of said current transformer is connected to one end of said capacitor charging coil through a resistor and the anode and the cathode of a diode.

25. An ignition system according to claim 8, wherein when a capacitor charging current flows in one of said plurality of charging circuits, the thyristors in at least two of said plurality of discharging circuits associated with the others of said plurality of charging circuits are controlled.

26. An ignition system according to claim 8, wherein, in each of said charging circuits, said current transformer comprises one primary winding and two secondary windings, wherein said two secondary windings are electrically connected to the respective thyristors in two different ones of said plurality of discharging circuits, and wherein when a capacitor charging current flows in one of said plurality of charging circuits, the thyristors in two of said plurality of discharging circuits associated with the others of said plurality of charging circuits are controlled.

27. An ignition system according to claim 8, wherein, in each of said charging circuits, the ends of said capacitor are interconnected through a resistor having a high resistance value to complete a closed circuit, and wherein the charge stored in said capacitor is discharged through said high resistance resistor.

28. An ignition system according to claim 2, wherein, in each of said charging circuits, said capacitor charging coil is connected through the primary winding of said transformer and an engine stopping switch to the capacitors in the others of said charging circuits.

29. An ignition system according to claim 6, wherein the output voltages of the secondary windings of said first and second transformers are respectively rectified through full-wave rectifiers each thereof having four diodes, and wherein the output terminals of said secondary windings are connected so as to supply control

voltages to the respective gates of said first and second thyristors.

30. An ignition system according to claim 6, wherein the ends of the secondary windings of said first and second transformers are respectively interconnected through respective rectifying diodes and the interconnections are respectively electrically connected to the gates of said first and second thyristors, and wherein the center points of the respective secondary windings of said first and second transformers are electrically connected to the respective cathodes of said first and second thyristors.

31. An ignition system according to claim 6, wherein each of said first and second thyristors consists of a bi-directional thyristor, and wherein the AC outputs of the respective secondary windings of said first and second transformers are applied to the respective gates of said first and second thyristors.

32. An ignition system according to claim 9, wherein, in the same polarity with that of said diode, a rectifying diode is connected in parallel with a series circuit consisting of said coil portions connected in parallel with the primary winding of said transformer and said rectifying means.

33. An ignition system according to claim 9, wherein a diode for passing only those half voltage waves of said two coil portions of said capacitor charging coil which are opposite in polarity to the charging half voltage waves thereof is connected in parallel with one of said two coil portions which is not connected in parallel with the primary winding of said transformer.

34. An ignition system according to claim 10, wherein, in each of said charging circuits, a diode for passing only those half voltage waves of said capacitor charging coil portions which are opposite in polarity to the charging half voltage waves thereof, is connected in parallel with one of said coil portions which is not connected in parallel with the primary winding of said transformer.

35. An ignition system according to claim 11, wherein diodes are connected in parallel with said coil portions of said first and second capacitor charging coils, respectively, which coil portions are not connected in parallel with the primary windings of said first and second transformers, respectively, said diodes passing only those half voltage waves which are opposite in polarity to the charging half voltage wave of said coil portions of said first and second capacitor charging coils.

36. An ignition system according to claim 4, wherein in parallel with a portion of said capacitor charging coil, there is connected a diode for passing only those half voltage waves of said coil portion which are opposite in polarity to the charging half voltage waves thereof.

37. An ignition system according to claim 5, wherein, in each of said charging circuits, there is connected, in parallel with a portion of said capacitor charging coil, a diode for passing only those half voltage waves of said coil portion which are opposite in polarity to the charging half voltage waves thereof.

38. An ignition system according to claim 6, wherein there are connected in parallel with portions of said first and second capacitor charging coils, respectively, a diodes for passing only those half voltage waves which are opposite in polarity to the charging half voltage waves of said coil portions.

39. An ignition system according to claim 9, wherein a diode is connected in parallel with said capacitor charging coil to pass only those half voltage waves of said capacitor charging coil which are opposite in polarity to the charging half voltage waves thereof.

40. An ignition system according to claim 10, wherein a diode is connected in parallel with each of said capacitor charging coils to pass only those half voltage waves of said capacitor charging coil which are opposite in polarity to the charging half voltage waves thereof.

41. An ignition system according to claim 11, wherein a diode is connected in parallel with each of said first and second capacitor charging coils to pass only those half voltage waves of each capacitor charging coil which are opposite in polarity to the charging half voltage waves thereof.

42. An ignition system according to claim 12, wherein, in parallel with said first coil portion of said capacitor charging coil having a higher number of turns, there is connected a diode for passing only those half voltage waves of said first coil portion which are opposite in polarity to the charging half voltage waves thereof.

43. An ignition system according to claim 13, wherein, in parallel with said first coil portion of each of said capacitor charging coils having a higher number of turns, there is connected a diode for passing only those half voltage waves of said first coil portion which are opposite in polarity to the charging half voltage waves thereof.

44. An ignition system according to claim 14, wherein, in parallel with said first coil portion with a higher number of turns of each of said first and second capacitor charging coils, there is connected a diode for passing only those half voltage waves of said first coil portion which are opposite in polarity to the charging half voltage waves thereof.

45. An ignition system according to claim 15, wherein, in parallel with said second coil portion of said capacitor charging coil having a smaller number of turns, there is connected a diode for passing only those half voltage waves of said second coil portion which are opposite in polarity to the charging half voltage waves thereof.

46. An ignition system according to claim 16, wherein, in parallel with said second coil portion with a smaller number of turns of each of said capacitor charging coils, there is connected a diode for passing only those half voltage waves of said second coil portion which are opposite in polarity to the charging half voltage waves thereof.

47. An ignition system according to claim 17, wherein, in parallel with said second coil portion with a smaller number of turns of each of said first and second capacitor charging coils, there is connected a diode for passing only those half voltage waves of said second coil portion which are opposite in polarity to the charging half voltage waves thereof.

48. An ignition system for internal combustion engines comprising: a first charging circuit including a series combination of a capacitor charging coil for generating an output by the rotation of a permanent magnet, first rectifying means for rectifying the generated output of said capacitor charging coil, and a first capacitor, the flow of current in said first charging circuit being directed from one end of said capacitor charging

coil to said first capacitor through said first rectifying means; a second charging circuit including a series combination of said capacitor charging coil, second rectifying means for rectifying the generated output of said capacitor charging coil, and a second capacitor, the flow of current in said second charging circuit being directed from the other end of said capacitor charging coil to said second capacitor through said second rectifying means; a first discharging circuit including a series combination of said first capacitor and a first thyristor having a gate to cause said first capacitor to discharge its stored charge upon conduction of said first thyristor; a second discharging circuit including a series combination of said second capacitor and a second thyristor having a gate to cause said second capacitor to discharge its stored charge upon conduction of said

second thyristor; first and second ignition coils each thereof having a primary winding and a secondary winding; and first and second transformers each thereof having a primary winding and a secondary winding, said primary windings being electrically connected to said capacitor charging coil to detect the generated output thereof, wherein the primary windings of said first and second ignition coils are respectively connected to form said first and second discharging circuits, wherein at least one spark plug is connected to each of the secondary windings of said first and second ignition coils, and wherein the secondary windings of said first and second transformers are electrically connected to the respective gates of said first and second thyristors.
